SCRAPER

Christian Erickson, Brooklyn, N. Y.

Application July 13, 1943, Serial No. 494,494

4 Claims. (Cl. 30—171)

My invention relates to improvements in hand scrapers of the general type forming the subject matter of my U. S. Patent No. 2,317,041, dated April 20, 1943, and over which the instant invention is designed as an improvement.

The primary object of the instant invention is to provide in such scrapers for simplifying the structure of the scraper blade holders so that the scraper blades may be more quickly and easily reversed and clamped in the holder, to strengthen the holders, adapt such scrapers for greater range of use and easier manipulation over surfaces being scraped, and for clamping in the holders double-edged blades of improved cross-sectional shape, adapting the blades for smoother and easier scraping, and to generally reduce manufacturing and replacement costs.

Other and subordinate objects are also comprehended by my invention, all of which, together with the precise nature of my improvements, will be readily understood when the succeeding description and claims are read with reference to the drawings accompanying and forming part of this specification.

In said drawings:

Figure 1 is a view in side elevation of a preferred form of my improved scraper,

Figure 2 is a view in top plan of the same,

Figure 3 is a view in longitudinal section taken on the line 3—3 of Figure 2,

Figure 4 is a view in end elevation looking at the front end of the scraper,

Figure 5 is a view in perspective of the scraper blade detached,

Figure 6 is a view in perspective of a modified form of the scraper blade,

Figure 7 is a fragmentary view in side elevation of a modified form of holder for the modified form of blade,

Figure 8 is a view in front elevation of the modified form of holder and blade,

Figure 9 is a view in perspective of another modified form of scraper blade,

Figure 10 is a fragmentary view in side elevation of still another modified form of holder and scraper blade,

Figure 11 is a fragmentary view in top plan of the holder and blade shown in Figure 10, and

Figure 12 is a view in perspective of the modified form of scraper blade shown in Figures 10 and 11.

Referring to the drawings by numerals, and first to Figures 1 to 5 thereof, in its preferred form my improved scraper comprises a holder designated generally 1 and including a body part

2, a handle 3, and a pair of upper and lower clamping plates 4, 5 for the scraper blade 6.

The body part is of elongated form and preferably made of wood, with a rounded rear end, as at 7, concave side portions 8 facilitating gripping the same with the hand, and a widened front end 9 having rabbeted top and bottom, curved faces 10, 11 converging to a sharp straight front edge 12 and terminating at the juncture thereof with the remainder of the body part in shoulders 13, 14, respectively. In the longitudinal center thereof, a pair of bolt holes 15 are provided in the body part 2 which open onto the top and bottom of said body part and are arranged one adjacent the transverse center of said body part and the other adjacent the rear end of said part. The bolt holes 15 are of keyhole form. A pair of countersinks 16 are provided in the top of the body part 2 around the bolt holes 15, and a pair of thin metal, keyhole wear plates 17 are fixed in said countersinks 16 below the top of the body part, as at 18, said plates surrounding the upper ends of the bolt holes 15.

The handle 3 is of gooseneck form and suitable wood with an enlarged flat, top front end 19 fitting flat against the bottom of the body part 2 from approximately the transverse center to the rear end of said body part. A pair of flat headed screw bolts 20 extend downwardly through the smaller parts of the bolt holes 15, with heads bearing on the plates 17, said bolts extending into bores 21 in the head 19 and being secured therein by nuts 22 countersunk in enlarged ends 23 of said bores. The handle 3, proper, slopes from the head 19 and from the body part 2 rearwardly and downwardly with a gradual inclination.

As will be apparent, by merely loosening the bolts 20 and shoving the handle 3 in a direction to enter the bolts in the larger parts of the bolt holes 15, said bolts may be withdrawn out of said bolt holes and the handle 3 thus easily and quickly detached, as occasion may require.

The scraper blade 6 is rectangular in shape, with a central, transversely S-shaped, channel-forming portion 24 and opposite side edge cutting portions 25 curved transversely oppositely, relatively, so that said portions 25 are slightly hooked transversely in opposite directions with respect to each other.

The clamping plates 4, 5 seat against the faces 10, 11 and converge forwardly, with the rear edges thereof seating against the shoulders 13, 14, and said plates extend across the front end 9 of the body part 2 from side to side thereof, and forwardly of said end. The upper plate 4 is formed

along its front edge with a pair of transversely extending, rounded ribs 26 interfitting with the channel-forming portions 24 on the top side of the scraper blade 6, and the lower clamping plate 5 is provided with a front edge groove 27, and a front edge rib 28, which interfits with said channel-forming portion 24 of said blade 6 on the bottom side of the said plate. Screws 29 adjacent the rear edges of said plates 4, 5 secure the same to the front end 9 of the body part 2. The upper plate 4 clears the top face 10, forwardly of its attaching screws 29, so that it may be flexed toward the lower plate 25 to clampingly engage the ribs 26 thereon and the groove 27 and rib 28 of the lower plate with opposite sides of the scraper blade 6. As best shown in Figures 1 and 3, the ribs 26 of the upper plate 4 and the groove 27 and rib 28 of the lower plate 5 mate with the portion 24 of the blade 6 in a plane inclined downwardly and forwardly of the horizontal plane of the body part 2, so that a leading side portion 25 of the blade 6 extends below the lower clamping plate 5 and curves downwardly and rearwardly relative thereto. The upper plate 4 is concaved in the rear of the ribs 26, as at 30, for clearance between said plate and the top face 10, to accommodate the other side portion 25 of said blade 6 between said upper plate and said face. A single screw bolt 31 extends through the clamping plates 4, 5 and through the front end 9 of the body part 2, forwardly of the screws 29, and in the longitudinal center of the body part, and provides for clamping the plates 4, 5 against the scraper blade 6, said bolt having its head and nut end suitably countersunk in said plates.

Obviously, the described scraper blade 6 may be reversed between the plates 4, 5 for use of either cutting side portion 25, as desired, and said blade is designed for flat scraping, as on floors or the like.

In the modified form of scraper shown in Figures 6, 7 and 8, the scraper blade 32 is generally rectangular, with a pair of closely spaced, channel-forming ribs 33 extending along each face thereof upon opposite sides of the longitudinal center of the blade, and said blade is generally S-shaped transversely to provide opposite side cutting portions 34 transversely curved oppositely, relatively, one of which is straight edged for flat scraping, and the other of which has a longitudinally convex edge for scraping, for instance, molding, not shown. The upper clamping plate 35, in this instance, is formed with a pair of grooves 36 in the front edge thereof for fitting over the ribs 33 on one side of the scraper blade 32, and the lower clamping plate 36 is provided with a transverse, front edge rib 37 fitting in between the ribs 33 on the other side of said blade, and also with a groove 38 adjacent to and parallel with said rib and fitting over the rib 33 on said other side of the scraper blade. The clamping plates 35, 37, in this instance, clamp the blade 32 in a plane inclined forwardly and upwardly of the horizontal plane of the body part 39 to dispose a cutting side of the blade 32 well forwardly of the plates 35, 37, and the front edge of the upper clamping plate 35 is thickened and extends forwardly past the lower clamping plate 37 to adequately back the blade 32 under downward pressure of the scraper against the work. Otherwise, the construction and arrangement is substantially as described with reference to the first described form of the invention.

In the form of the invention shown in Figure 9, a scraper blade 40 is provided of generally rec-

tangular shape, in edge contour, and including a central, longitudinal, channel-forming, transversely U-shaped rib 41, and a pair of coplanar, flat portions 42 upon opposite sides of said rib 41 terminating in oblique angled, straight, side cutting portions 42' on one and the same side of said blade.

In Figures 10 and 11, a modified form of scraper blade is provided in which the side cutting portions 42', such as shown in Figure 9, are eliminated, and flat portions 44 upon opposite sides of a rib 45, similar to rib 41, terminate in cutting edges 46, 47, the edge 46 being convex for use on molding and the like, and the edge 47 being straight for flat scraping. In this form of the invention, the upper clamping plate is provided with a front edge, downwardly and rearwardly turned rib 49 adapted to fit into the channel 50 formed by the rib 45, and the lower clamping plate 51 is formed with a front edge groove 52 for receiving said rib 45, the rib 49 and groove 52 clamping the blade so that its flat, coplanar, side cutting portions 43 incline forwardly and downwardly of the horizontal plane of the body part 53. The top face 54 of the front end 55 of said body part 53 is notched transversely, as at 56, and clears the upper plate 48 so that a flat portion 43 of the blade may be accommodated between said plate 48 and said end 55, or a flat portion 42 and cutting portion 42' of the blade 40. Also, in this form of the invention, the upper clamping plate 43 coacts with a portion of the top face 54 to clamp a flat portion of the blade therebetween, and the leading edge of the front end 55 is grooved across the same, as at 56, to seat the rib 45, or rib 41, as the case may be.

The foregoing will, it is believed, suffice to impart a clear understanding of my invention without further explanation.

Manifestly, the invention is susceptible of modification without departing from the inventive concept, and right is herein reserved to such modifications as fall within the scope of the appended claims.

What I claim is:

1. In a scraper of the class described, an elongated holder including a body part having a reduced front end provided with top and bottom faces converging forwardly, a pair of upper and lower clamping plates opposed to said top and bottom faces, respectively, in forwardly converging relation and extending forwardly of said front end, and a double edged scraper blade 55 clamped between said plates forwardly of said front end and in a plane oblique to the horizontal plane of said body part, said blade having a central bent portion forming a rib on one side of the blade and a groove on the other side and said upper and lower plates having a rib and groove extending across the front end thereof, respectively, and mating with said groove and rib of the blade.
2. In a scraper of the class described, an elongated holder including a body part having a reduced front end provided with forwardly converging top and bottom faces, a pair of upper and lower clamping plates opposed to said top and bottom faces, respectively, in forwardly converging relation and having complementary ribs and grooves extending across the front edges thereof, and a scraper blade having a transversely S-shaped central portion interfitting with said ribs and grooves, and a pair of side cutting portions, one extending forwardly of said plates

and the other interposed between the upper clamping plate and said top face, said upper clamping plate having a portion clearing said top face to provide a space for said other cutting portion.

3. In a scraper of the class described, a holder including a body part having a front end provided with top and bottom faces converging forwardly, a pair of upper and lower clamping plates opposed to the top and bottom faces, respectively, and extending forwardly of said front end, and a transversely S-shaped scraper blade interposed between said plates forwardly of said end and having a pair of longitudinally extending ribs on each side thereof closely spaced in each pair upon opposite sides of the longitudinal center of the blade, the upper plate having grooves therein interfitting with the pair of ribs on one side of the blade, and the lower plate having a rib thereon fitting in between the pair

20 of ribs on the other side of the blade, and a groove fitting over one rib of the last-mentioned pair.

4. In a scraper of the class described, a holder 5 including an elongated body part having a front end provided with forwardly converging top and bottom faces, a pair of upper and lower clamping plates opposed to said top and bottom faces, respectively, and extending forwardly of said 10 front end in converging relation, the upper plate having a rearwardly and downwardly inclined front edge rib, and the lower plate having a front edge groove opposed to said rib, and a scraper blade having a longitudinal central groove and rib interfitting with the first-mentioned rib and groove, one of said plates having a portion clearing said top face to provide a space between the plate and said face, and said blade having an edge extending into said face.

CHRISTIAN ERICKSEN.
